HENRY A. WISE WOOD, OF NEW YORK, N. Y., ASSIGNOR TO WOOD NEWSPAPER MACHINERY CORPORATION, OF NEW YORK, N. Y., A CORPORATION OF VIRGINIA

METAL PUMP

Application filed June 30, 1927. Serial No. 202,554.

This invention relates to a pump for delivering molten metal and is particularly adapted for stereotyping purposes.

The principal object of the invention is to insure that upon each stroke the pump will deliver the same amount of metal irrespective of the level of the metal in the melting pot in which the pump is located. This is done by maintaining a constant level of molten metal in a chamber connected with the pump and spout. For this purpose the invention also involves means for constantly feeding metal into said chamber from the melting pot and through the chamber to the pump barrel.

Other objects and advantages of the invention will appear hereinafter.

Reference is to be had to the accompanying drawings, in which

20 Fig. 1 is a plan of a pump constructed in accordance with this invention;

Fig. 2 is a sectional view on the line 2—2 of Fig. 1; and

25 Figs. 3 and 4 are similar sectional views showing modifications coming within the scope of this invention.

In automatic stereotype machines it is desirable that the same quantity of molten metal be delivered with each stroke of the 30 pump. Attempts have been made to do this by improving the construction of the piston and pump barrel and controlling the stroke, but these improvements fail to prevent some variation in the amount of metal delivered, 35 due to the varying level of the molten metal in the melting pot and therefore in the barrel and spout.

In ordinary pumps the level of the metal within the pump, at the beginning of its operating stroke, is the same as the level of the metal in the pot in which the pump is located. Differences in this level necessarily vary the amount delivered from the spout. 40 Although a constant amount of metal is displaced by the pump at each stroke, a certain portion of it is returned to the pump with the return of the piston. That portion is governed by the quantity of metal contained within the spout between its highest point 45 near the delivery and the normal level of the

metal within the pot. It is impossible to maintain a constant level in the melting pot itself on account of the withdrawal of the metal at each operation and the replenishing of the metal. This invention is designed to 55 compensate for this variation in an automatic pump.

Referring first to Figs. 1 and 2, an ordinary melting pot 2 is illustrated having a pump barrel 1 therein. The pump is provided with a delivery spout 3 for the usual purpose. In the pump is a piston 4 having perforations or ports 9 therethrough, and a piston rod 5 which is operated by a lever 6 and connections 7. The latter is as usual 60 connected with the cam of an automatic plate casting machine, not illustrated herein. The piston 4 is loose on a reduced portion of the piston rod 5. Fixed on the end of that rod is a valve 8 adapted to close the ports 9 65 at certain times as will appear. The metal is introduced into the pump barrel 1 through an inlet 10 which is controlled by a valve 11 freely mounted on a stem and adapted to move up and down with the current of liquid 70 metal.

The metal is supplied to the pump barrel through this inlet 10 by a pump, as for example, an ordinary gear pump 12. This pump is driven from a suitable source of 75 power constantly by a chain 13, preferably operated by the plate casting machine. The metal is delivered from the gear pump through a conduit 14 into a chamber 15 directly above the pump barrel and containing 80 in its bottom the inlet 10. This chamber is provided with an over-flow conduit 16 large enough to take care of the metal delivered to the chamber. Therefore, the metal is maintained at a constant level by this over-flow 85 conduit, as shown in Fig. 2, irrespective of any changes in the level of the molten metal in the pot.

When the connection 7 is pulled downward 90 by the operation of the casting machine, the piston rod 5 of course, moves up and takes with it the valve 8. This valve is pressed up against the bottom of the piston 4 and closes the ports 9 and then lifts the piston. This, 95 of course, forces the entire body of metal 100

above the piston upwardly. This flow immediately closes the valve 11 so that the entire body of metal is forced into the spout. When the piston is in the position shown in Fig. 2, the inlet valve being open, the metal in the pump barrel is in communication with that contained in the chamber 15 so that a constant level is maintained. The same level is maintained in the spout. Therefore, regardless of the amount of metal in the melting pot 2, the metal in the pump and spout is always kept constant. From this it follows that the quantity of metal discharged with each operation of the piston is independent of the level of the metal in the melting pot 2.

In the form shown in Fig. 3, some of the parts above described are shown in the same arrangement, but instead of the gear pump I have shown an additional piston 19 below the piston 4 and in alignment with it. This piston 19 is located in an auxiliary pump barrel 18 beneath the pump barrel 1. This necessitates the raising of the pump barrel 1 with its delivery and return conduits somewhat higher in the melting pot.

The piston 19 is provided with ports 20 and a valve 21 attached to the lower end of the piston rod 5. The piston 4 is provided with the ports 9 and valve 8 to permit this piston to descend without any back pressure which might be developed by the metal contained beneath it on account of leakage around the piston.

The piston 4 moves upwardly to discharge metal and the piston 19 is drawn upwardly after a slight dwell. This piston 19 thereby sucks metal into the chamber beneath it through inlet port 22, in the bottom of the barrel 18. On the return stroke of the piston rod, the valve 23 is closed by the action of the pressure of the metal above it, and the metal contained in the barrel 18 is forced through a conduit 25. This metal runs over into the chamber 15 and through the inlet port 10 into the barrel as before. This keeps the level in the chamber 15 up to the bottom of the conduit 16 as stated. In this case the bottom of the lower pump barrel 18 is closed except for the valve and ports, and also the bottom of the pump barrel 1 is closed by the top of the barrel 18.

In the form shown in Fig. 4, the arrangement is similar except that an auxiliary piston 26 is placed alongside of the main barrel 1 and is operated by a reversing lever 24 which is connected with the piston rod 5 and operated thereby. This is merely a different arrangement of the parts, but the operation is the same, the valve 27 taking the place of the valve 23. The modification otherwise is obvious.

In all these forms the varying levels of metal in the melting pot are compensated for by maintaining a constant level in the chamber above the pump barrel. This latter cham-

ber surrounds the pump and spout and communicates with them through the inlet 10, thus making the amount of delivery independent of variations in the level of the metal within the melting pot.

Although I have illustrated and described only three forms of the invention, I am aware of the fact that other changes can be made therein by any person skilled in the art without departing from the scope of the invention as expressed in the claims. Therefore I do not wish to be limited to the exact form shown, but what I do claim is:

1. In a pump for delivering molten metal, the combination with a pump barrel, a piston in the barrel for raising the metal therein and delivering it, a chamber above the pump barrel for receiving the metal and delivering it into the barrel, and means for keeping the level of the molten metal and its volume in said chamber constant when the pump is not pumping metal.

2. In a pump for delivering molten metal, the combination with a pump barrel and means for introducing metal into the barrel from above, of a piston in the barrel for raising the metal therein and delivering it, and a chamber extending above the barrel having an outlet by which the level of the molten metal in said chamber is rendered constant, said chamber being located in position for receiving the metal before it is introduced into the pump barrel.

3. In a pump for delivering molten metal, the combination with a barrel, a piston therein, and means for operating the piston to force the metal from the barrel to discharge it, of means for forcing molten metal into the barrel, and a chamber above the barrel receiving the metal from said forcing means and discharging it into the barrel, said chamber having an outlet of large capacity, whereby the level of metal in the chamber will remain constant at the bottom of said outlet.

4. In a pump for delivering molten metal, the combination with a barrel, a piston thereon, and means for operating the piston to force the metal from the barrel to discharge it, of means for forcing molten metal from a melting pot into the barrel, said barrel having a port through which the metal can escape into it, and a chamber above the barrel receiving the metal from said forcing means and discharging through said port into the barrel, said chamber having an outlet of large capacity, whereby the level of metal in the chamber will remain constant irrespective of the level of metal in the pot outside the pump barrel.

5. In a device of the character described, the combination with a melting pot, of a pump located therein projecting down into the molten metal in the pot, said pump comprising a barrel extending below the metal in

the pot, a piston in the barrel, means for operating the piston, a chamber on the top of the barrel, a port in the bottom of the chamber leading into the barrel, a valve for automatically closing the port when the piston is raised, said chamber having an outlet capable of carrying away the metal introduced into it and adapted to insure a constant level of the metal in the chamber, and means for introducing metal from the pot into said chamber.

6. In a device of the character described, the combination with a melting pot, of a pump located therein, said pump comprising a barrel, a piston in the barrel, means for operating the piston, a chamber on the top of the barrel, a port in the bottom of the chamber leading into the barrel, said chamber having an outlet capable of carrying away the metal introduced into it to insure a constant level of the metal in the chamber, and means for introducing metal from the pot into said chamber.

7. In a device of the character described, the combination with a melting pot, of a pump located therein, a chamber at the top of the pump, a port in the bottom of said chamber, an outlet from the chamber capable of carrying away the metal introduced into the chamber to insure a constant level of the metal in the pump.

In testimony whereof I have hereunto affixed my signature.

HENRY A. WISE WOOD.
